PANTY CONSTRUCTION

Adelaide S. Mann, New York, N. Y.

Application September 12, 1947, Serial No. 773,579

5 Claims. (Cl. 128—287)

1

This invention relates to women's panties.

It is an object of the present invention to provide a woman's pantie of a type adapted to be attached and supported from any undergarment such as a corset or girdle or from a garter belt and which is free of material around the hips and legs and may be worn without an elastic waist band.

It is another object of the present invention to provide a woman's pantie which will absorb perspiration, prevent chafing, gives all the protection of the usual type of pantie, can be easily laundered, quickly dried, small enough to carry in a purse or handbag, attached with great ease, serves as a support for a sanitary pad making it unnecessary to wear uncomfortable sanitary belts, formed of pliable material to be stretched tightly over the undersides of the legs, capable of adjustment, free from wrinkling and forming into a roll, and inexpensive to manufacture.

For a better understanding of the invention, reference may be had to the following detailed description taken in connection with the accompanying drawing, in which

Fig. 1 is a perspective view of the lower end of a corset with the woman's pantie of the present type connected thereto,

Fig. 2 is a plan view of the pantie embodying the features of the present invention,

Fig. 3 is a transverse cross-sectional view taken on line 3—3 of Fig. 2,

Fig. 4 is a perspective view of the front pad which is connected to the corset and to which the forward end of the pantie is attached and of a special clip which is applied when a sanitary pad is used,

Fig. 5 is a plan view of the rear pad which is attached to the corset with one of the attaching elements for the sanitary pad connected thereon,

Fig. 6 is a plan view of one of the sanitary pad clips,

Fig. 7 is a perspective view of a modified form of pantie wherein a half circle of material is connected to the sides of the pantie to give added protection and trim,

Fig. 8 is a fragmentary and perspective view of a pad and of a pantie with a modified means for the attachment of the pantie to the pad.

Fig. 9 is an elevational view of a modified form of a sanitary pad clip.

Referring now to the figures, 15 represents a corset or girdle having the usual fastening strips 16 for connecting the side ends together and adapted to be extended tightly about the body of the wearer. The usual garters 17 are con-

nected to the lower end of the corset to extend therebelow and in a location to be connected to stockings. To the rear of the corset there is sewed a tab 18, Fig. 5, having three fastening tapes 19 secured thereto at laterally spaced positions thereon. These fastening tapes provide three loops 22 into any one of which a hook 24 connected preferably by an elastic 25 to pantie 26, may be attached whereby to support the pantie upon the tab at the rear of the corset. The center strap of the tab 18 serves for the connection to the tab of a sanitary napkin or pad clip 27 shown in Figs. 5 and 6. This clip has a metal loop 28 with a point 29 thereon for receiving the end of the sanitary pad to retain the same. The loop 28 is connected to an elastic strap 31 on which is a hook 32 which can be connected to any one of the loops 22 of the intermediate tape 19. By having a double connection of the pantie 18, the pantie will be prevented from swinging from side to side between the legs.

The pantie is made of any pliable or stretchable material or material cut on a bias. The 25 pieces are arranged to permit the maximum stretch longitudinally of the panties as indicated by the arrow 33. The sides of the pieces are sewed together as indicated at 34 and between the pieces and at the center thereof there is 30 extended a non-stretchable tape or strip 35 which will prevent the pantie from wrinkling or shaping into a roll between the legs and thus holds the shape of the pantie. This tape or strip 35 prevents too much stretching of the material at the center. The strip 35 is sewed to one of the pieces as indicated at 36 in Fig. 3 thereby to permit the other layer of the material to be free of the strip and free to stretch. Tapes 37 of non-stretchable material extend across the rear 35 end of the pantie and on opposite sides of the same and into which elastic piece 25 can be extended and secured. The pantie may be made from a single layer of material with center strip 35, secured to it.

45 At the front end of the pantie, tapes 38 are extended thereacross and from which a strap 39 preferably of resilient material is extended. The strap 39 has a hook 40 for securing the pantie to any one of several loops 41 in a tape 42 on a tab 43 which is attached to the front of the corset 15. While the hook 40 is connected to one loop 41, another loop may have a sanitary pad clip 27 attached to it for the securement of a sanitary pad.

50 It should be apparent that the pantie is of simple construction, that it is pliable and easily at-

tached to the corset, reinforced to limit the stretching of the same so as to keep the pliable edges tightly against the inner sides of the legs and wherein provision is made for the attachment of a sanitary pad within the same.

In Fig. 7, there is shown a modified form of the invention wherein there has been secured to the side edges of the pantie, a half circle of similar pliable material of soft crepe, silk, or lace whereby to provide an edge trim 44 and a more elaborate pantie. The trim will also provide additional cover for the larger size person. This trim may be stitched between the layers of the pantie material as the pantie is assembled or added by an additional stitching to already assembled layers of the pantie material. The trim will give to the pantie a more fanciful appearance as well as added protection.

In Fig. 8, there is shown a modified form of fastening device which may be used in place of the hooks 24, 32 and 40. This fastening device comprises a piece 45 having a key hole slot 46 adapted to receive and retain a button projection 47 on the tabs which are fixed to the corset. Both the hook 32 and the piece 45 are to provide an easy means for the attachment of the pantie to the undergarment and at the same time that cannot be easily disengaged while the pantie is being worn. Other suitable fastening devices may be used. The tabs are supplied with the pantie and can be readily and easily fastened to any undergarment owned by the purchaser of the pantie. By a simple sewing operation either by hand or machine the tabs are made secure to the garment.

These tabs control the ease with which the pantie is worn and detached. The pantie can be adjusted on the tabs to render it comfortable and still give all the protection of the usual pantie without unwanted material about the hips and without the uncomfortable waist band. The pantie can be used when wearing any form of foundation garment, such as a corset, girdle, or garter belt.

In Fig. 9, there is shown a modified form of sanitary pad clip which may be used instead of the clip 27 shown in Fig. 6. This clip includes a wire 51 having spring portions 52 between which cloth material can be extended to retain pad. With this arrangement the cloth material does not have to be pierced as with the point 29 when using the clip 27. The member 51 will have the same hook 32 on its upper end.

It will be understood that the tabs 18 and 43 will be preferably secured to the garment by stitching but may be secured by a safety pin or similar detachable device so that the stitching will be unnecessary.

It should be further understood that the material of which the pantie is made can be rubberized or moisture proof so as to prevent the pantie from becoming stained or easily soiled.

While various changes may be made in the detail construction, it shall be understood that such changes shall be within the spirit and scope of the present invention as defined by the appended claims.

I claim:

1. A pantie comprising a layer of pliable and stretchable material, fastening elements connected to the ends of the material for securing the pantie to the front and rear of a garment extended about the wearer so that the pantie will extend between the inner sides of the legs of the wearer and with sufficient tightness to be

stretched thereover, and said fastening means including tabs having vertically-extending tapes having plurality of vertically-spaced loops adapted to be fixed to the garment and a stretchable piece secured to the pantie and having a hook thereon adapted for engagement with any one of the loops of the tapes.

2. A pantie as defined in claim 1 and sanitary pad clips adapted to be extended into any of the loops of the fastening tape not used by the pantie hooks and adapted to retain a sanitary pad within the pantie and against longitudinal displacement from between the legs of the wearer.

3. A woman's pantie comprising two layers of stretchable material secured together at their edges and adapted to be extended between the legs of the wearer, means adapted for the securement of the ends of the pantie with a garment on the wearer's body, and a central non-stretchable tape independent of the securement means extending from one end of the pantie to the other and connected to the ends of the layers whereby to limit the stretching of the pantie at the center thereof and to maintain its shape, and said tape being disposed between the layers of the pantie and secured to one of the layers of the material thereby leaving the other layer free to be completely stretched.

4. A woman's pantie comprising double layers of pliable and stretchable material secured together about the edges, reinforcing means at the opposite ends of the layers, a central non-stretchable tape connected to the front and rear ends of the layers, fastening devices connected to the reinforcing means and adapted to secure the pantie to the front and rear of a garment extended about the wearer so that the pantie will extend between the inner sides of the legs of the wearer and with sufficient tightness to be stretched thereover, and half circle pieces of soft material connected along the edges of the pantie layers to provide added protection and trim.

5. A pantie construction adapted to be connected to any garment or support extended about a wearer which comprises a piece of pliable and stretchable material adapted to stretch longitudinally at the edges thereof to a greater extent than along its longitudinal middle section, said pantie being adapted to pass between the legs of the wearer, tabs adapted to be secured respectively to the front and rear of the garment or support, a non-stretchable tape extending longitudinally along the middle of the piece and connected to the ends thereof whereby to prevent the stretching of the piece at the middle thereof and to hold the shape of the pantie, and releasable fastening elements connected respectively to the ends of the stretchable piece and to the tabs whereby the stretchable piece and tape can be released from the tabs when the tabs have been made secure to the garment.
